TRAFFIC LIGHTING SYSTEM

Henry Denis, Brooklyn, N. Y.

Application November 1, 1943, Serial No. 508,486

4 Claims. (Cl. 177—327)

This invention relates to new and useful improvements in a traffic lighting system.

More specifically, the invention proposes the construction of a traffic lighting system characterized by a casing having a plurality of side panels each having superimposed red and green signals to be clearly viewed, and a hinged door to permit changing of the electric bulbs and for cleaning the interior of said casing.

Still further it is proposed to provide lights within the casing for the superimposed red and green signals arranged in a manner to permit them to be alternately and simultaneously in operation, and more specifically, permitting first the red to be lit, then the red and green, and finally the green.

Still further it is proposed to arrange shields in such a manner that they will each include a stationary shield and a movable inner shield arranged to move concentrically with relation to the outer shield and to have these shields normally located directly above the signals in a manner to cover the top areas thereof.

Still further it is proposed that the inner shield be manually moved into a position beneath the signal and upper shield and to characterize each of the shields by flexible central sections and rigid hingedly mounted side sections normally urged towards each other in a manner so that when the inner shield is turned to its lowered position the shields will swing towards each other and partially cover the signal lights.

It is proposed that the shields be in their normal superimposed position during normal times, and that the inner shield be moved to its lowered position during blackout periods for partially covering the signals, reducing the quantity of light emanating therefrom while at the same time permitting the signals to be viewed by motorists approaching the signal.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an elevational view of a traffic light constructed in accordance with this invention.

Fig. 2 is a view similar to Fig. 1 but illustrating a shifted position of the parts.

Fig. 3 is a vertical sectional view taken substantially on the line 3—3 of Fig. 1.

Fig. 4 is an enlarged vertical sectional view taken substantially on the line 4—4 of Fig. 3.

Fig. 5 is a view, per se, of the inner shield and its controlling ring gear.

The traffic lighting system, according to this invention, includes a casing 10 mounted upon

the top end of a hollow vertical standard 11 and having a plurality of side panels 12 each of which has superimposed red signals 13 and green signals 14. The interior of the casing 10 is provided with a horizontal wall 14^a at a point between the signals 13 and 14.

Light bulbs 15 are mounted on the top and bottom faces of the horizontal wall 14^a and are connected with a source of power and controlling mechanism (not shown on the drawing) for permitting the signals 13 and 14 to operate alternately and simultaneously.

One of these panels 12 is hinged to the casing at 12^a and is provided with a suitable locking handle 12^b, so that this panel may act as a door to permit changing the bulb 15 and closing the interior of the said casing. The desired arrangement is to have both the upper and lower sections lit only when the direction of traffic is about to change.

When the upper section alone is lit and off, the north and south traffic have the green light and is moving, then the east and west traffic has the red light and is stopped. Shortly before the light in the upper section goes out, the lower section lights up. This brings out a red and green light in all directions, warning the north and south motorist that they will soon have a total red light against them and prepare to stop at the nearest intersection. At the same time it lets the east and west bound motorist know that they will soon have a green light, and may prepare to start. Then the light in the upper section goes out and the east and west traffic will move on the green light and the north and south traffic is stopped. After a set time, the upper section will light before the light in the lower section goes out to give notice to the motorist to get ready to start or stop. This changing of the lighting from the upper to the lower section and the lower to the upper section is repeated in accordance to the time setting or speed of the drum switch.

This arrangement may function as a simple container or a compound shield 16 may be provided for each of the signals 13 and 14 upon the four panels of the casing 10. Each compound signal comprises a substantially semi-circular outer stationary shield 17 mounted directly on the panels 12 of the casing 10 directly above each of the signals.

Each of the outer shields 17 consists of a flexible central section 17^a and rigid hingedly mounted side sections 17^b. These side sections 17^b are hingedly supported upon hinged structures 18 having springs 19 which tend to urge the sections 17^b slightly inwards, as shown in Fig. 2.

Each of the compound shields 16 further includes an inner substantially semi-circular shield

20 each of which consists of a flexible central section 20^a and rigid hingedly mounted outer side sections 20^b. The rigid outer side sections 20^b are pivotally attached by means of hinged structures 21 to a ring 22 mounted on the inner face of the panels 12 of the casing 10. The hinged structures 21 are provided with springs 23 which normally tend to urge the rigid side sections 20^b into slightly inwardly directed positions, as shown in Fig. 2. The ring 22 is rotatively supported upon a metallic frame 24 which supports the glass forming the signals 13 and 14. The metallic frame 24 is supported by several brackets 25 upon the inner face of the panels of the casing 10. These brackets 25 are extended around the rings 22 and in no way interfere with a free rotation thereof. Extending from the frame 24 there is a substantially semi-circular stationary cam 26. This cam 26 is arranged over the top of the signals 13 and 14 and is designed to be engaged by the inner shields 20 for the purpose of urging the rigid side sections 20^b of the inner shields 20 into an extended position against the action of the spring 23. This will extend the inner shields 20, as shown in Fig. 1, and in turn the inner shields 20 will urge the side sections 17^b of the outer shields 17 into their extended positions against the action of their respective springs 19.

The operation of the device is as follows:

Normally, the shields 17 and 20, which comprise the compound shields 16, are one within the other permitting the signals 13 and 14 to be clearly viewed by approaching motorists. However, during blackout periods it is possible to manually turn the inner shields 20 as permitted by the rotatively supported rings 22 relative to the outer shield 17 to locate the inner shields 20 adjacent the bottom of the signals 13 and 14 clear of the cams 26. In this position the springs 19 and 23 of the hinged structures 18 and 21 which support the side sections of the shields will urge the shields into a position in which they partially cover the signals 13 and 14 to limit the amount of light which will pass from the signals 13 and 14. It will be noted that these shields do not completely cover the signals 13 and 14, as shown in Fig. 2, permitting some of the light to pass therefrom to be viewed by passing motorists.

At the end of the blackout period the inner shields 20 may be turned back to their normal position within the shields 17 and on the cams 26. The cams 26 will then function to urge the side sections of the shields into their completely extended position shown in Fig. 1.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A traffic lighting system, comprising a casing having a signal, and a compound shield for said signal, comprising a substantially semi-circular outer stationary shield having a flexible central section and rigid hingedly mounted side sections, a substantially semi-circular inner shield within said outer shield and having a flexible

central section and rigid hingedly mounted side sections, a substantially semi-circular stationary cam within said inner shield for holding said hingedly mounted side sections of said inner shield extended, said extended sections of said inner shield engaging said sections of said outer shield holding them extended, resilient means for urging said shield sections collapsed, means for rotatively supporting said inner shield to be manually turnable to a position free of said cam.

2. A traffic lighting system, comprising a casing having a signal, and a compound shield for said signal, comprising a substantially semi-circular outer stationary shield having a flexible central section and rigid hingedly mounted side sections, a substantially semi-circular inner shield within said outer shield and having a flexible central section and rigid hingedly mounted side sections, a substantially semi-circular stationary cam within said inner shield for holding said hingedly mounted side sections of said inner shield extended, said extended sections of said inner shield engaging said sections of said outer shield holding them extended, resilient means for urging said shield sections collapsed, means for rotatively supporting said inner shield to be manually turnable to a position free of said cam, each of said rigid hingedly mounted side sections being pivotally supported upon hinges and said resilient means being arranged concentric with the pivot of said hinges.

3. A traffic lighting system, comprising a casing having a signal, and a compound shield for said signal, comprising a substantially semi-circular outer stationary shield having a flexible central section and rigid hingedly mounted side sections, a substantially semi-circular inner shield within said outer shield and having a flexible central section and rigid hingedly mounted side sections, a substantially semi-circular stationary cam within said inner shield for holding said hingedly mounted side sections of said inner shield extended, said extended sections of said inner shield engaging said sections of said outer shield holding them extended, resilient means for urging said shield sections collapsed, said inner shield being manually turnable to a position free of said cam, each of said inner shields being mounted upon a rotatively supported ring comprising the means for manually turnably mounting said inner shields.

4. A traffic lighting system, comprising a casing having a signal, and a compound shield for said signal, comprising a substantially semi-circular outer stationary shield having a flexible central section and rigid hingedly mounted side sections, a substantially semi-circular inner shield within said outer shield and having a flexible central section and rigid hingedly mounted side sections, a substantially semi-circular stationary cam within said inner shield for holding said hingedly mounted side sections of said inner shield extended, said extended sections of said inner shield engaging said sections of said outer shield holding them extended, resilient means for urging said shield sections collapsed, said inner shield being manually turnable to a position free of said cam, each of said inner shields being mounted upon a ring, and means rotatively supporting said ring.

HENRY DENIS.
